HYDRAULIC REMOTE CONTROL SYSTEM

Lemuel E. Dougherty, Fairhope, Ala.

Application April 29, 1943, Serial No. 484,998

9 Claims. (Cl. 60—54.5)

This invention may be considered a further improvement or development of my inventions regarding hydraulic remote controls as shown in my applications for U. S. Patent Serial No. 449,942, filed July 6, 1942, and Serial No. 459,176, filed September 21, 1942.

The primary object in both of the above mentioned inventions is to provide an automatic locking means at the receiver end of the system to hold the receiver or operated end of the system from any movement due to the exertion of external forces thereon or from any expansion, contraction or leakage of fluid from the system.

While the locking of the receiver or operated end of the system when the transmitter handle was not being operated served to eliminate errors in position of the receiver element during this interval, it nevertheless resulted in the transmitter element taking up the error due to expansion or contraction, thus resulting in lack of synchronism between the two elements. It is therefore the principal object of this invention to provide means whereby the expansion or contraction of the main body of fluid, namely that which is contained in the connecting duct between the transmitter and the receiver, is free to expand and contract during normal times, that is, in the intervals when the transmitter handle is not being operated, without, however, destroying synchronism which exists at all times between the transmitter element and the receiver element.

For this purpose I utilize a separate expansion and compression system with which the connecting duct is normally in engagement when the transmitter handle is not being actuated so that all expansion and contraction of the fluid in the connecting duct will be taken up by this expansion chamber at the same time both the transmitter and the receiver elements are disconnected from the connecting duct. Means are then provided whereby upon actuation of the transmitter handle in one direction or the other, the connecting duct is automatically disconnected from the expansion chamber and connected to the transmitter and to the receiver so that all movements of the transmitter will be instantaneously transmitted to the receiver.

It is a further object of this invention to provide a plurality of transmission systems, each system comprising a transmitter, a receiver and a duct connecting said transmitter and receiver, together with a common expansion chamber with which all of said ducts are normally connected. Actuation of the transmitter of any system disconnects the respective duct from the common expansion chamber and connects it to the transmitter and receiver of that system.

Further objects and advantages of this invention will become apparent in the following detailed description thereof:

In the accompanying drawings, Fig. 1 is a cross sectional view of the transmitter assemblage.

Fig. 2 is a top sectional view of the transmitter assemblage taken on the line 2—2 of Fig. 1.

Fig. 3 is a cross sectional view of a part of the transmitter assemblage showing a modified form of valve assemblage.

Fig. 4 is a cross sectional view of a part of the transmitter assemblage showing a modified form of valve assemblage.

Fig. 5 is a cross sectional view of the receiver assemblage with locking valve attached.

Fig. 6 is a diagrammatic illustration of a plurality of independent control systems connected to a single compressor unit.

Referring to Fig. 1, the transmitter assemblage is comprised of three main parts: the transmitter cylinder and piston assembly; a compressor cylinder and piston assembly; and a valve assembly which controls the connection of either of these cylinders to the receiver assemblage.

The transmitter cylinder and piston assembly is very similar to that shown in aforementioned patent applications and consists primarily of the frame 10, cylinder 11 with the piston 12 slidable therein. The spring 26 is held under compression upon the rod 24, being seated at one end upon the disc 27 and at the other end in the collar 23. This collar is pivotally mounted in the frame at the points 75—75 as shown in Fig. 2. The rod 24 is pivotally connected at 21 to the operating lever 18 which is pivoted in frame 10 at 22 and connected to the piston by means of the rod 18.

This linkage between the spring and the piston provides a substantially constant pressure force upon the fluid in the cylinder 11 below the piston. That part of the cylinder between the upper and lower heads of the piston, which are equipped with the seals 31 and 16, respectively, is filled with fluid under very low pressure by gravity or otherwise from a supply tank 17 through passage 16 and the port 11. The proper quantity of fluid in the system is maintained by means of the synchronizing valve 15 in the head of the piston. The fixed rod 14 extends transversely across the cylinder and through the slot 13 in the piston. Movement of the piston to the upward extent of its stroke causes this valve to be opened by

striking against the rod 14, thus connecting the supply tank or reservoir 17 to the lower or pressure part of the cylinder. Synchronization between the receiver and transmitter can thus be established by moving the transmitter piston to the upward extent of its stroke and allowing it to return through the action of the spring 26 until the valve 15 is closed.

The compressor is constructed similarly to the transmitter, insofar as the spring and linkage to the piston is concerned, so that the fluid in the

compressor cylinder 33 is maintained at a substantially constant pressure substantially equal to the pressure on the fluid in the transmitter cylinder 11. For this purpose a spring 45 is held under compression upon the rod 43, being seated at one end upon the disc 46 and at the other end in the collar 42. This collar is pivotally mounted in the frame 10 at the points 14-14 as shown in Fig. 2. The rod 43 is pivotally connected at 41 to the lever 39 which is pivoted in frame 10 at 40 and connected to the piston 35 by means of the rod 36 at point 38, said rod being connected to the piston at pivot 37.

The transmitter valve assembly consists of valves 63 and 60 which are attached to the diaphragms 50 and 51, respectively. The spring 65, under compression, is seated against the diaphragm 50, tending to close valve 63. The spring 70, under compression, is seated against diaphragm 51, tending to open valve 60. Fluid pressure from the transmitter cylinder enters through the passage 48 to the chambers below the diaphragms so that the force of the fluid pressure against the diaphragms is in opposite relation to the force of the springs acting thereon. Under the normal fluid pressure maintained in the transmitter cylinder this force from the fluid pressure against the diaphragm 50 is slightly greater than the opposite force of the spring 65 so that the valve 63 is normally open. The force of the spring 70 is slightly greater than the force of the normal fluid pressure against diaphragm 51 so that the valve 60 is normally held open. The ball check valve 57 is normally held closed by the spring 58 but will open upon a predetermined increase in pressure from the transmitter cylinder. The ball check valve 55 is normally held closed by the spring 54 but will open upon a predetermined decrease in fluid pressure from the transmitter. Fluid connection from the transmitter assemblage to the receiver assemblage is by means of the connecting tube or duct 72.

With the system at rest, that is, when no motion is being transmitted, fluid connection from the receiver is through the connecting tube 72, the passage 56, the open valve 60, the passage 62, the open valve 63 and the passage 64 to the compressor cylinder 33. As described in my herein-before mentioned co-pending applications, and as will be again described hereinafter, the receiver is normally held against movement by the locking valve assemblage shown in Fig. 5. Therefore, it is seen that any change in volume of fluid in the connecting tube 72 will cause movement of the compressor piston 35 only, and will not affect the position of the transmitter. When it is desired to transmit movement between the transmitter and receiver, force exerted upon the transmitter operating lever and consequent increase or decrease of fluid pressure in the transmitter cylinder will cause one of the valves to close, thus disconnecting the compressor cylinder 33 from the connecting tube 72, and fluid is transferred from the transmitter to the receiver by passage through the check valves 57 or 55. Force exerted downwardly on the transmitter piston will increase the fluid pressure in the cylinder 11. When this pressure has increased sufficiently to open check valve 57 and allow flow to the receiver, this increased pressure upon diaphragm 51 will have closed the valve 60. Force exerted on the transmitter operating lever so as to move the transmitter piston upwardly, thus decreasing the pressure in the cylinder, causes valve 63 to

close before the check valve 55 has opened. It is thus seen that when it is desired to transmit motion between the transmitter and receiver, one of the transmitter valves will close and disconnect the compressor from the system, but as soon as such movement is stopped, both of these valves will be open and the compressor connected to the system. Any change in volume of fluid in the connecting line taking place when the transmitter is not being operated, will, therefore, be compensated for by movement of the compressor piston, and no movement will take place in the transmitter because the latter is disconnected from duct 72 by the valves 55 and 57.

In Fig. 5 there is shown a receiver and locking valve assemblage of the type described in my said co-pending patent applications, which may be used in this system. I here illustrate the fluid locking means of my application, Serial No. 449,942, but it will be apparent to those skilled in the art that the locking means of my later filed application, Serial No. 459,176, can also be used in the system.

In this lever assemblage a spring 145 is held under compression upon the rod 146 being seated at one end upon the disc 147 and at the other end in the collar 142. This collar is pivotally mounted in the frame 130 on pivots (not shown) similar to pivots 74 and 75. The rod 143 is pivotally connected at 139 to the lever 138 which is pivoted in the frame 130 at 140 and connected to the piston 133 by means of rod 135 which is pivoted at 137 to lever 138, and at 134 to the piston 133. This linkage is similar to that employed in the transmitter, the spring thus normally maintaining fluid pressure in the receiver cylinder substantially constant and equal to the fluid pressure maintained in the transmitter and compressor cylinders.

Normally when the transmitter handle is not being operated the pressure of spring 45 upon piston 35 places under pressure the fluid which communicates with expansion reservoir 33 and extends from this reservoir by way of passage 64, open valve 63, passage 62, open valve 60, passage 56 and connecting duct 72 to the receiver assemblage. The receiver piston 133, however, is normally cut off from the duct 72 by reason of the fact that said duct communicates with the receiver cylinder by way of valves 154 and 158, which are normally closed. The valve 154 is normally closed because the force of the transmitter fluid pressure upon diaphragm 164 is slightly greater than the oppositely acting force of the compression spring 166. The valve 158 is normally closed because the force of the compression spring 167 is greater than the force of the transmitter fluid pressure upon the diaphragm 165. Under normal fluid pressure in the system both of these valves are closed, thus effectively disconnecting the receiver piston from duct 72 and locking the receiver against movement. A predetermined increase or decrease in fluid pressure from the transmitter will cause one of these valves to open, thus connecting the transmitter and receiver cylinders and allowing flow of fluid and transmittal of motion between them. Thus, movement of the transmitter handle in a direction to increase the pressure in duct 72 increases the pressure upon diaphragm 165 to open valve 158 and establish communication with the receiver piston. Movement of the transmitter handle in the opposite direction to decrease the pressure in duct 72 enables spring 166 to overcome the pressure on the diaphragm and

open valve 154, and thus establish communication between the receiver piston and the duct 72.

The operation of the device as thus far described is therefore as follows:

Normally the connecting duct 72 is disconnected from both the transmitter piston 12 and the receiver piston 133, but is connected to the expansion chamber 33 acting upon the piston 35. Thus, two conditions normally prevail. First, the transmitter and the receiver are locked in which ever positions they have been set. Second, any expansion or contraction in the main body of fluid in the system which is in the connecting duct will have no effect upon either the transmitter or the receiver, and thus will not introduce an error in the positioning of either of these elements, but such expansion and contraction will take place entirely in the expansion chamber where it will act upon the piston 35. As soon, however, as the transmitter lever is actuated in one direction or the other, the expansion chamber is disconnected from the connecting duct 72 (by closing valve 63 or valve 60), and the said connecting duct is connected to the transmitter (through valve 55 or valve 57), and to the receiver (through valve 154 or 158). All this is performed automatically merely at the actuation of the transmitter handle which serves to increase or decrease the pressure which normally is maintained in the connecting duct 72 by the spring 45 acting upon piston 35.

Referring to Fig. 3 this transmitter valve assemblage is very similar to that in Fig. 1 already described, insofar as the valves are concerned. In this modified form of construction I use fluid pressure from the transmitter cylinder through passages 81 and 83 on one side of diaphragms 85 and 86, and fluid pressure from the compressor cylinder through passages 79 and 95 upon the other side of these diaphragms. As these fluid pressures from the transmitter and the compressor are substantially equal and balance each other, it is only necessary to provide springs of sufficient force to assure that the valves are held open when the system is at rest. The spring 93 normally holds valve 92 open but an increase of fluid pressure from the transmitter cylinder will cause this valve to close. The spring 87 normally holds valve 97 open but a decrease in fluid pressure from the transmitter will cause this valve to close. With valves 92 and 97 open, and valves 103 and 106 (corresponding to valves 57 and 55) closed, the connecting duct 72 is connected to the reservoir 33 by way of passages 107, 98, valve 87, valve 92 and passage 94. When either valve 92 or valve 97 closes due to increase or decrease of pressure caused by operation of the transmitter handle, then the expansion chamber 33 is cut off from duct 72, and the transmitter chamber 11 is connected to said duct by way of passages 81, 83 and 102, and valve 103 or 106.

One advantage of this form of construction is that it is unnecessary to accurately balance the force of the springs against the fluid pressure force on the diaphragms as done in the construction shown in Fig. 1. It is only necessary to provide springs which will normally hold the valves open and allow them to close upon small changes in the transmitter fluid pressure. Another advantage of this form of construction is that in case of a lack of a proper fluid pressure from the compressor, which might occur due to a leakage of fluid or other cause, the valves will auto-

matically close and disconnect the compressor from the system.

Referring to Fig. 4, in this form of construction a piston type sliding valve is used rather than the poppet valves and diaphragms as heretofore described. The sliding piston 118 normally closes the passage 111 between the transmitter cylinder 11 and the connecting duct 72 to the receiver. A port is provided which normally allows passage of fluid through the passages 123, 124 and 125 to the compressor or expansion cylinder 33. The passage 124 provides fluid pressure from the compressor cylinder to the chamber 121, thus acting against one end of the piston 118. The passage 112 provides fluid pressure from the transmitter cylinder to the chamber 113, acting upon the opposite end of the piston. The springs 115 and 120 are pre-loaded and seat upon the washers 117 and 119 which are slidable in the chambers 113 and 121. These chambers, being larger in diameter than the piston, provide a shoulder upon which these washers are seated. Thus there is normally no load from the springs upon the piston 118, but as soon as this piston starts to move it picks up the load of one of the springs. A predetermined increase in fluid pressure from the transmitter cylinder, acting against the end of the piston 118 will cause it to move against the force of the spring 120 until its port allows flow of fluid through the passage 111, thus connecting the transmitter to the receiver. Before this passage is open, the piston will have moved sufficiently to close the passage 123 and thus disconnect the compressor cylinder from the system. A decrease in fluid pressure from the transmitter cylinder will cause the piston to move in the opposite direction, thus again opening the passage 111 and closing the passage 123. One advantage this form of valve construction has is that it is slightly simpler and less expensive to manufacture. Another advantage is that the passage to the compressor is positively closed before the passage to the transmitter is opened.

Although I have here illustrated a compressor constructed as an integral part of the transmitter assemblage, it is of course apparent that it need not be so constructed, but may be made as a separate unit and connected to the valve in the transmitter assembly by means of a connecting tube. By following such practice, a single compressor unit may be used with a plurality of transmitter units. The volume of the compressor unit must, of course, be sufficient to accommodate the change in volume of the fluid in the connecting tubes between all of the transmitter and receiver assemblages.

In Fig. 6 is diagrammatically illustrated such an installation of a plurality of hydraulic control systems connected to a single compressor unit. The transmitter assemblages 183a, 184a, 185a and 186a are connected to the receiver assemblages 183b, 184b, 185b, and 186b by the respective connection tubes 187, 188, 189 and 190. A compressor unit 181 is connected by means of a tube 195 to the valve assemblies in the transmitter units. The fluid supply tank or reservoir 180 is connected by the tube 182 to the fluid supply ports of the transmitter cylinders. Such construction and installation is particularly desirable for use in aircraft or other installations where a number of control systems are used.

In accordance with the provisions of the patent statutes, I have herein described the principle and operation of my invention, together with the

apparatus which I now consider to represent the best embodiment thereof, but I desire to have it understood that the apparatus shown is only illustrative and that the invention can be carried out by other equivalent means. Also, while it is designed to use the various features and elements in the combination and relations described, some of these may be altered and others omitted without interfering with the more general results outlined, and the invention extends to such use.

Having described my invention what I desire and claim to secure by Letters Patent is:

1. In a fluid transmission system comprising a transmitter, a receiver, and a duct adapted to connect the transmitter and the receiver, an expansion chamber, means for normally connecting said duct to said chamber and disconnecting said duct from said transmitter and said receiver, and means responsive to the actuation of said transmitter for disconnecting said duct from said chamber and connecting said duct to said transmitter and said receiver.

2. In a fluid transmission system comprising a transmitter, a receiver, and a duct adapted to connect the transmitter and the receiver, an expansion chamber, means for normally connecting said duct to said chamber and disconnecting said duct from said transmitter and said receiver, and means responsive to the actuation of said transmitter for disconnecting said duct from said chamber and connecting said duct to said transmitter and said receiver, said last named means including valve mechanisms at the transmitter and at the receiver, and means responsive to the actuation of said transmitter for actuating said mechanisms.

3. In a fluid transmission system comprising a transmitter, a receiver, and a duct adapted to connect the transmitter and the receiver, an expansion chamber, means for normally connecting said duct to said chamber and disconnecting said duct from said transmitter and said receiver, and means responsive to the actuation of said transmitter for disconnecting said duct from said chamber and connecting said duct to said transmitter and said receiver, said last named means including a set of oppositely acting valve mechanisms at the transmitter and a second set of oppositely acting valve mechanisms at the receiver, and means responsive to the actuation of said transmitter in one direction for actuating certain of said mechanisms at the transmitter and at the receiver, and means responsive to the actuation of said transmitter in the other direction for actuating the other of said mechanisms at the transmitter and at the receiver.

4. In a fluid transmission system comprising a transmitter, a receiver, and a duct adapted to connect the transmitter and the receiver, an expansion chamber, means for normally connecting said duct to said chamber and disconnecting said duct from said transmitter and said receiver, and means responsive to the actuation of said transmitter for disconnecting said duct from said chamber and connecting said duct to said transmitter and said receiver, said last named means including a set of oppositely acting valve mechanisms at the transmitter and a second set of oppositely acting valve mechanisms at the receiver, and means responsive to the actuation of said transmitter to increase the fluid pressure in the system for actuating certain of said mechanisms at the transmitter and at the receiver, and means responsive to the actuation of said transmitter

to decrease the fluid pressure in the system for actuating the other of said mechanisms at the transmitter and at the receiver.

5. In a control mechanism, a plurality of fluid transmission systems, each system comprising a transmitter, a receiver and a duct adapted to connect the transmitter and the receiver, a single expansion chamber, means for normally connecting each of said ducts to said chamber and normally disconnecting said ducts from the transmitter and the receiver, and means responsive to the actuation of each of said transmitters for disconnecting the respective duct from said chamber and connecting said duct to the respective transmitter and receiver.

6. In a control mechanism, a plurality of fluid transmission systems, each system comprising a transmitter, a receiver and a duct adapted to connect the transmitter and the receiver, a single expansion chamber, means for normally connecting each of said ducts to said chamber and normally disconnecting said ducts from the transmitter and the receiver, and means responsive to the actuation of each of said transmitters for disconnecting the respective duct from said chamber and connecting said duct to the respective transmitter and receiver only while said transmitter is being actuated.

7. In a control mechanism, a plurality of fluid transmission systems, each system comprising a transmitter, a receiver and a duct adapted to connect the transmitter and the receiver, a common reservoir for maintaining all of said systems filled with fluid, a single expansion chamber, means for normally connecting each of said ducts to said chamber and normally disconnecting said ducts from the transmitter and the receiver, and means responsive to the actuation of each of said transmitters for disconnecting the respective duct from said chamber and connecting said duct to the respective transmitter and receiver.

8. In a fluid transmission system comprising a transmitter, a receiver and a duct adapted to connect the transmitter and the receiver, a reservoir for maintaining said system filled with fluid, means for maintaining the fluid in said system under pressure, an expansion chamber, means for maintaining said chamber under pressure substantially equal to the pressure of the fluid in said system, means for normally connecting said duct to said chamber and disconnecting said duct from said transmitter and said receiver, and means responsive to the actuation of said transmitter and effective as long as said transmitter is being actuated for disconnecting said duct from said chamber and connecting said duct to said transmitter and said receiver.

9. In a fluid transmission system comprising a transmitter, a receiver and a duct adapted to connect the transmitter and the receiver, a reservoir for maintaining said system filled with fluid, means for maintaining the fluid in said system under pressure, an expansion chamber, means for maintaining said chamber under pressure substantially equal to the pressure of the fluid in said system, means for normally connecting said duct to said chamber and disconnecting said duct from said transmitter and said receiver, and means responsive to actuation of said transmitter for disconnecting said duct from said chamber and connecting said duct to said transmitter and said receiver.

LEMU E. DOUGHERTY.
